UNITED STATES PATENT OFFICE.

HOWARD M. DUDLEY, OF PHILADELPHIA, PENNSYLVANIA.

DYEING-MACHINE.

1,261,500.

Specification of Letters Patent. Patented Apr. 2, 1918.

Application filed April 28, 1917. Serial No. 165,074.

To all whom it may concern:

Be it known that I, HOWARD M. DUDLEY, a citizen of the United States, and a resident of Philadelphia, in the county of Philadelphia and State of Pennsylvania, have invented certain new and useful Improvements in Dyeing-Machines, of which the following is a specification.

My invention relates to improvements in dyeing machines and refers particularly to dyeing machines adapted to the dyeing of piece goods.

In the dyeing of goods in the piece, the greatest care must be exercised in order to cause complete penetration of the dyestuff and even shades.

The dyeings of many dyestuffs require an after-treatment with such products as metallic-salts, or oxidizing agents in order to develop the best results. It is also necessary to thoroughly wash the goods at various stages of the operation and to dry them when finished.

As each one of these operations has an effect upon the results, it is essential that all of the treatments be uniform throughout the fiber and that they be readily controlled.

One object of my invention is a device in which the piece goods may be uniformly subjected to a solution of a dye.

Another object of my invention is a device in which thorough penetration of textile fabrics may be effected.

Another object of my invention is a device in which dyed fabrics may be uniformly and thoroughly after-treated with a liquid, air or gas.

Another object of my invention is a device in which the fabrics may be thoroughly dried.

Another object of my invention is a device in which fabrics may be dyed, washed, after-treated and dried in a thorough and uniform manner without handling them.

Another object of my invention is a means whereby the device may be readily and effectively adjusted to conform with fabrics of different widths.

Other objects of my invention will be evident upon a consideration of my specification and claims.

In the accompanying drawings, which illustrate several modifications of the device of my invention, similar parts are designated by similar numerals.

Figure 1 is a longitudinal section through the line 1—1 of Fig. 2.

Fig. 2 is a cross-section through the line 2—2 of Fig. 1.

Fig. 3 is a cross-section through the line 3—3 of Fig. 1, with portions omitted for purpose of clearness of representation.

Fig. 4 is an enlarged view of one portion of the device shown in Fig. 1.

Fig. 5 is a cross-section through the line 5—5 of Fig. 4.

The particular form of my device, as illustrated, comprises a dyeing chamber formed by the bottom member 7 and the top member 8, hingedly attached thereto and capable of being held in intimate contact by means of the screw bolts 9, 9. A pipe 10, opening into the top of the dyeing chamber is connected to a system (not shown) whereby the liquid passing from the dyeing chamber may be returned for repassage through said chamber.

Within the dyeing chamber is a reel, around which the cloth to be dyed or treated is wound, comprising a cylindrical plate 17 having shells 19, 19^A at the ends and integral therewith and an integral flange at each end which supports the foraminous plate 18. The end flanges 16, 16^A are fixedly attached to shells 19, 19^A. Fixedly attached to the shell 19^A is a cogged wheel 20, meshing with the worm gear 21 which is fixedly attached to the shaft 22, from which a revolute movement may be imparted to the shells 19, 19^A and the reel. Extending into the shells 19, 19^A are the pipes 28, 28^A around which the shells 19, 19^A are revoluble. The pipes 28, 28^A are connected to sources of liquid and air supply.

In order that a liquid may be impinged equally over the entire inner face of the foraminous plate 17, a series of tubes 31, 31^A, 32, 32^A connect the entire inner face of the foraminous plate 17 with the exterior portion of the chamber formed by the shells 19, 19^A, the tubes from the chamber of the shell 19 alternating upon the foraminous plate 17 with the tubes from the chamber of the shell 19^A, *i. e.* adjacent tube openings upon the plate 17 extend oppositely to each other and outwardly through the shells 19, 19^A. Within each tube 31, 31^A, 32, 32^A is a series of saw toothed baffle-plates 33, 33, 33 of varying lengths.

Two perforated steam pipes 61, 61^A enter

the chamber 57 between the foraminous plates 17, 18. The method of introducing steam into the chamber 57 during the revolution of the reel is shown in Figs. 4 and 5. 5 One end of one of the pipes 34, 34 is connected with the pipe 61^A. The other end of the pipe 34 is integral with the annular member 35 having a by-pass 36. The member 35 is revoluble within the bushing 37, 10 fixedly attached to the stationary pipe 28^A. The steam pipe 38 having the valve 39 enters the chamber 40, which in turn is connected with the annular chamber 41. One end of the member 35 revolves in the stuffing box 15 42, while the other end revolves within the chamber 43 of the bushing 37. It is evident that while the pipe 34 and the member 35 are revolving, steam may be allowed to enter through the pipe 38, the chamber 40, 20 the annular member 41 and the by-pass 36 into the pipe 34. The other pipe 34 is connected to convey steam to pipe 61.

In order to reduce the width of the foraminous plate 18 through which the liquor 25 passes to coincide with the width of the fabric to be treated, the following device is employed: A series of annular members 44, 45, 46, 44^A, 45^A, 46^A are slidable upon each other, 46 and 46^A being slidable upon the 30 annular plate 18. A series of threaded bolts 47, 47^A passes through holes in the members 16, 16^A and thread with threaded holes in the members 44, 45, 46, 44^A, 45^A, 46^A. The washers 48, 48 are fixedly attached to the 35 bolts 47, 47^A. The exterior ends of each of the threaded bolts 47, 47^A carries a cog-wheel 49 and a square head 50, capable of receiving a wrench for turning purposes. A chain belt 51 connects the bolts 47, 47, 47, 40 47^A, 47^A, 47^A of each member 44, 45, 46, 44^A, 45^A, 46^A and meshes therewith so that turning one bolt will turn the other bolts of that particular slidable member equally, thus insuring an accurate movement of said 45 member.

The foraminous plate 17 has a series of parallel longitudinal openings or slits 52, 52 through which a liquid can pass.

The foraminous plate 18 has a series of 50 upwardly and downwardly divergent openings 53, 53 through which a liquid can pass.

A valve 54 allows the liquor to be drained from the dyeing chamber.

The cloth 55 is wrapped or rolled around 55 the foraminous plate 18, and is surrounded by a link belt 56 which has openings similar to those in the plate 18 for the passage of a liquid.

The operation of the device is as follows: 60 The slidable members 44, 45, 46, 44^A, 45^A, 46^A are slidably separated from each other, the cloth or fabric 55 is wound around the foraminous plate 18, and the link chain cover 56 tightly wound around the cloth 55. 65 The members 44, 45, 46, 44^A, 45^A, 46^A, or

such of them as are necessary, are moved inwardly toward the cloth by turning the screw bolts 47, 47^A until they abut firmly upon it, thus preventing any of the liquor from passing outwardly between the cloth 70 and the slidable members. The lid 8 is then closed, steam introduced through the pipes 61, 61^A, dye liquid forced through the tubes 31, 32, 31^A, 32^A, and the reel and the cloth contained thereon, with the other attached 75 members, revolved by means of the gear 21 and the wheel 20. As the liquid passes out through the pipe 10, it is returned by any suitable means for the purpose of continuing its circulation through the device. 80

By these means the liquid is forced through the openings in the foraminous plate, into the chamber 57 and from thence through the openings in the foraminous plate 18 and there distributed equally over 85 and through the fabric 55 and through the cover 56. The fabric may be washed by forcing fresh water through the pipes 28, 28^A and the device and it may be dried by forcing air through the pipes 28, 28^A and 90 the device.

I do not limit myself to the particular size, shape, number or arrangement of parts as shown and described, all of which may be varied without going beyond the scope of 95 my invention as described and claimed.

What is claimed, is:

1. In a dyeing machine, in combination, a foraminous cylinder capable of having a fabric rolled thereon, annular members inwardly slidable over said cylinder and abuttable thereon, annular members inwardly slidable over said annular members and abuttable thereon, the inner faces of all of said annular members forming a surface capable of abutment upon the edges of fabric rolled upon the cylinder, means for moving the annular members and means for maintaining the annular members in abutment against the fabric. 110

2. In a dyeing machine, in combination, a foraminous cylinder capable of having a fabric rolled thereon, an annular member at each end of the cylinder and slidably movable thereon, means for moving the annular members over the cylinder, an annular member slidably movable over each of the first-mentioned annular members, means for moving these annular members over the first-mentioned annular members so that the inner faces of the two series of annular members will form a single surface and means whereby the two series of annular members may be locked in this position. 115

3. In a dyeing machine, in combination, a foraminous cylinder capable of having a fabric rolled thereon, annular members inwardly slidable over said cylinder and abuttable thereon, annular members inwardly slidable over said annular members and 120

130

abuttable thereon, the inner faces of all of said annular members forming a surface capable of abutment upon the edges of fabric rolled upon the cylinder, a series of moving means whereby each annular member may be slidably moved, means whereby a movement given any one of the moving means of an annular member will be transmitted equally to the other moving means of that member, and means for locking the annular members in any predetermined position.

4. In a dyeing machine, in combination, a foraminous cylinder capable of having a fabric rolled thereon, annular members inwardly slideable over said cylinder and abuttable thereon, annular members inwardly slideable over said annular members and abuttable thereon, the inner faces of all of said annular members forming a surface capable of abutment upon the edges of fabric rolled upon the cylinder, a series of screw-bolts whereby each annular member may be moved to any desired position and maintained therein, and means whereby the turning of any screw-bolt of a series will turn the other screw-bolts of that series equally.

5. In a dyeing machine, in combination, a dyeing receptacle, a foraminous cylinder revoluble within the receptacle, a second foraminous cylinder spaced from the first-mentioned cylinder and revoluble therewith, means for forcing a liquid through the second cylinder into said space and from thence through the first cylinder during the revolution of the cylinders, means for introducing steam into the space between the two cylinders during their revolution, and means for decreasing the openings in the first cyl-

inder so that all of the liquid forced therethrough must pass through fabric rolled thereon.

6. In a dyeing machine, in combination, a dyeing receptacle, a foraminous cylinder revoluble therein, a second foraminous cylinder spaced from the first-mentioned cylinder and revoluble therewith, a series of tubes connecting the entire inner face of the second cylinder with a source of liquid supply, means for forcing a liquid through the tubes during the revolution of the cylinders, and adjustable means movable upon and over the first cylinder to prevent the passage of liquid through any of the openings therein except those covered by a fabric rolled upon said cylinder.

7. In a dyeing machine, in combination, a dyeing receptacle, a foraminous cylinder revoluble therein, a second foraminous cylinder spaced from the first-mentioned cylinder and revoluble therewith, a series of tubes connecting the entire inner face of the second cylinder with a source of liquid supply, adjacent tubes upon the face of the second cylinder extending in opposite directions through the reel to such sources of liquid supply, said tubes being revoluble with the cylinders, means for introducing steam into the space between the cylinders during their revolution, and means for decreasing the number of openings in the first cylinder through which the liquid can pass.

Signed at New York city, in the county of New York and State of New York this 16th day of April, 1917.

HOWARD M. DUDLEY.
